[57] CLAIM

The ornamental design for a file clip, as shown and described.

DESCRIPTION

FIG. 1 is a left front perspective view of a file clip showing my new design, the structure depicted by means of broken lines being for environmental purposes only and forming no part of the claimed design;

FIG. 2 is a right side elevational view hereof, with the left side elevational view being a mirror image thereof;

FIG. 3 is a front elevational view thereof, with the rear elevational view being a mirror image thereof;

FIG. 4 is a top plan view thereof; and,

FIG. 5 is a bottom plan view thereof.
